(57) **CLAIM**

The ornamental design for a sports bottle, as shown and described.

DESCRIPTION

FIG. 1 is a perspective view of a sports bottle showing the design.

FIG. 2 is a left elevation view of the sports bottle of FIG. 1.

FIG. 3 is a right elevation view of the sports bottle of FIG. 1.

FIG. 4 is a front elevation view of the sports bottle of FIG. 1.

FIG. 5 is a rear elevation view of the sports bottle of FIG. 1.

FIG. 6 is a top plan view of the sports bottle of FIG. 1.

FIG. 7 is a bottom plan view of the sports bottle of FIG. 1.

FIG. 8 is a perspective view of the sports bottle of FIG. 1, shown together with an associated cap, in broken line.

FIG. 9 is a left elevation view of the sports bottle of FIG. 1, shown together with an associated cap in broken line.

FIG. 10 is a right elevation view of the sports bottle of FIG. 1, shown together with an associated cap in broken line.

FIG. 11 is a front elevation view of the sports bottle of FIG. 1, shown together with an associated cap in broken line.

FIG. 12 is a rear elevation view of the sports bottle of FIG. 1, shown together with an associated cap in broken line.

FIG. 13 is a top plan view of the sports bottle of FIG. 1, shown together with an associated cap in broken line; and,

FIG. 14 is a bottom plan view of the sports bottle of FIG. 1, shown together with an associated cap in broken line.

The dashed lines shown in the drawings illustrate portions of the sports bottle (e.g., the neck and bottom portions of the bottle) that form no part of the presently claimed design (FIGS. 1-14) and illustrate environmental structure of an associated cap (FIGS. 8-14) that forms no part of the presently claimed design. The shading lines shown in the drawings represent the approximate three-dimensional contour of the claimed design and are not intended to indicate surface decoration.
